Carpets

EX

OR D 5,642

No. 5,642.

Mar. 12, 1872.

UNITED STATES PATENT OFFICE.

ARTHUR M. KING, OF KIDDERMINSTER, ENGLAND, ASSIGNOR TO HENRY JECKS DIXON & SONS, OF SAME PLACE.

DESIGN FOR A CARPET-PATTERN.

Specification forming part of Design No. 5,642, dated March 12, 1872.

To all whom it may concern:

Be it known that I, ARTHUR MAZEPPA KING, of Kidderminster, county of Worcester, England, have invented a new and original Design for Carpets; and I do hereby declare that the following is a full, clear, and exact description thereof, which will enable others skilled in the art to make and use the same, reference being had to the accompanying photograph illustration forming part of the specification.

This invention relates to a new design for a carpet, and more particularly to two groups of figures therein represented.

The group A consists of a central square, *a*, with a cross, *b*, at each end, the cross being embraced in a Gothic arch, *c*, which is ornamented as shown. From the sides of the square *a* project narrow bands *d d*, which con-

nect the several squares together, and are ornamented in the middle, as shown. The group B consists of a rectangular middle portion, *e*, narrow sides *f f*, and ornamental scroll *g*, as shown.

I claim as my invention—

1. The design of the ornamental group A, as shown.
2. The design of the ornamental group B, as shown.
3. The design for the carpet containing the groups A and B, as shown.

ARTHUR MAZEPPA KING.
